DESIGN FOR A PLAYSUIT

Rose Jacobson, New York, N. Y.

Application January 19, 1942, Serial No. 105,292

Term of patent 3½ years

To all whom it may concern:

Be it known that I, Rose Jacobson, a citizen of the United States of America, residing in New York city, county of Bronx, and State of New York, have invented a new, original, and ornamental Design for a Playsuit, of which the following is a specification, reference being had to the accompanying drawing, forming part thereof, wherein,

I claim:

The ornamental design for a playsuit, substantially as shown and described.

ROSE JACOBSON.
